United States Patent Office

Des. 228,486
Patented Oct. 2, 1973

228,486

PULL

Lee Richard Chasen, Port Chester, N.Y., assignor to Coats & Clark, Inc., New York, N.Y.

Filed Dec. 23, 1971, Ser. No. 211,854

Term of patent 14 years

Int. Cl. D8—06

U.S. Cl. D8—139

Fig. 1.

Fig. 2.

Fig. 3.

FIG. 1 is a front view of a pull;
FIG. 2 is a back view of the pull shown in FIG. 1; and
FIG. 3 is a side view of the pull shown in FIG. 1 (both side views and top view being the same).

I claim:

The ornamental design for a pull, as shown and described.
